UNITED STATES PATENT OFFICE.

JESSE L. LAMONT, OF ATKINSON, ILLINOIS.

CORN-HARVESTER.

SPECIFICATION forming part of Letters Patent No. 378,551, dated February 28, 1883.

Application filed February 18, 1887. Serial No. 228,101. (No model.)

To all whom it may concern:

Be it known that I, JESSE L. LAMONT, a citizen of the United States, residing at Atkinson, Henry county, Illinois, have invented certain new and useful Improvements in Corn-Harvesters, of which the following is a specification, reference being had to the accompanying drawings, forming part thereof, in which—

Figure 1 is a plan view of my improved machine, a part being broken away to show more clearly the pinion on the inner roller. Fig. 2 is a longitudinal vertical sectional view of the same on the line $x-x$, Fig. 1. Fig. 3 is a detail rear view of the same, parts being broken away to show the carrier belt. Fig. 4 is a longitudinal vertical sectional view on the line $y-y$, Fig. 1. Fig. 5 is a transverse sectional view through two pairs of the rollers, their shields and the finger-carrying belt, and the supporting rods and the finger-separating rods. Fig. 6 is a detail perspective view of a portion of the roller-carrying frame, the supporting-wheel at the outer side of the same, and the adjusting mechanism therefor. Fig. 7 is a detail view of portions of the frame which carries the driving-wheels, adjustable roller-carrying frame, and the devices for adjusting the latter with regard to the former. Fig. 8 is a perspective view of the main frame and part of the roller-carrying frame, showing the means for adjusting the latter frame with respect to the former.

The object of my invention is to provide a corn-harvesting machine which is capable of simultaneously removing the ear from the stalk and husking it, the husked ears being pushed rearward and delivered to an elevator or conveyer mechanism which will deliver the ears to a wagon or other suitable receptacle.

The invention will first be described, and then specifically pointed out in the claims.

A represents the main frame, consisting of the inner and outer side bars A' A' the front and rear end bars A^2 A^2 , and the intermediate longitudinal bar, A^x , on which is journaled the axle a , carrying the drive-wheels a' a' and the gear a^2 . In rear of the gear a^2 and meshing therewith is mounted the pinion a^3 , the shaft of which also carries a sprocket-wheel, a^4 . B represents the adjustable frame, consisting of parallel outer and inner side bars B' B' and a rear cross-bar, this frame being con-

nected at its rear left-hand corner with the adjacent corner of the main frame A by means of the short bars B' B' , which form a continuation of the inner side bar A' and end bar, A^2 , respectively, as shown in Fig. 1. The ends of the bars B' B' have vertical recesses to receive the vertical guide-posts A^3 on the ends of the bars A' A^2 , respectively. 55

The forward adjacent corners of the frames A B are connected, and the latter is rendered adjustable on the former, by the mechanism shown in Figs. 1 and 7, where the guide-bar A^3 is apertured, as is also the recessed end of the inner side bar of the frame B to receive the pin A^4 . The outer side of the frame B is supported by means of the wheel b , which is journaled on a block, b' , which may be adjusted vertically in the slotted guide C, the arms of which are passed through a vertical dovetail recess in the outer side bar of the frame B, the side bar and arms being apertured to receive the bolts c , as shown in Fig. 6. The block b' is provided with a dovetail clamping-plate, b^2 , 75 which embraces the guide C below the frame and is adjustably connected therewith by means of the set screws b^3 , which pass through the ends of the clamp and bear against the inclined sides of the guide C, as shown also in Fig. 6. 80

The frame B is adjusted vertically at its inner side by means of an elbow-lever, F, which is fulcrumed to a support attached to the rear part of the inner side bar A' of the frame A. 85 To the short arm of the elbow-lever F is hinged the end of a connecting-rod, H, the other end of the said rod being connected to the inner side bar of the frame B. The elbow-lever F is held in any desired position by the detent-lever I, which engages with the toothed rack-bar J, attached to the side bar A' , whereby, by depressing the long arm of the said lever, the rear inner corner of the frame will be raised and held in any desired position by means of the detent and toothed rack; but the forward end of the frame B must be raised by hand and the pin A^4 inserted in the proper apertures according to the height desired, and the outer side of the frame B must be raised or lowered by first adjusting the guide C, when all minor adjustments of the wheel may be effected through the medium of the adjustable block b' and its clamp and set-screws. 90 95 100

The forward end of the adjustable frame B is open, and near the rear end thereof is attached a cross-piece, N, in bearings upon which revolve the rear parts of three pairs of horizontal fluted or ribbed rollers, O. The forward ends of the rollers O are tapered, and the tapered ends of the outer rollers revolve in bearings on the rear ends of the guides P, which incline outward, and are attached at their forward ends to the bolts or arms Q at the inner side of the forward ends of the side bars of the frame B. These bolts or arms Q also pass through the slotted inclined frames R, which have a free movement thereon and in inclined recesses in said side bars. (See Figs. 1 and 2.)

The tapered forward ends of the inner rollers of the side or outer pairs revolve in bearings in the upturned forward ends of the longitudinally-extending guide-rods T, which are secured at their rear ends to the rear end of the frame B. To the forward ends of each pair of the said rods T are secured the rear ends of the V-shaped guides S, the forward ends of which project in front of the rollers to guide the cornstalks into the space between the middle pair of rollers, and, in connection with the guide P, also guide the cornstalks into the spaces between the outer pairs of rollers during the forward movement of the machine.

The rear ends of the rollers O are provided with the bevel-pinion V, the teeth of which mesh with the teeth of the larger bevel gear-wheels W, attached to the shaft X in such position that the rollers of each pair will be revolved toward each other at their upper sides in opposite directions to draw the cornstalks that pass in between the said pairs of rollers downward. The shaft X revolves in bearings attached to the rear part of the frame B and extends at its inner end within the frame A, but is not connected thereto. The inner end of the shaft is provided with a sprocket-wheel, Y, which is connected with the sprocket-wheel a^4 by the chain Z, as shown in Fig. 1.

The upper sides of the rear parts of the rollers O are covered by the plate T', and projecting from the front edge of this plate are the curved shields O', which are secured at their front ends by means of their projecting arms O ^{2} to the upturned ends of the rods T and to the rear ends of the guides P, as shown in Figs. 1 and 4. The upper surfaces of the shields O' are each provided with a longitudinal guide-rib, O ^{2} . The spaces between the adjacent edges of each pair of shields and their ribs form troughs to receive the ears of corn, as will be more fully explained hereinafter.

The shaft X is provided between the toothed faces of each pair of gear-wheels W with a plain roller or pulley, X', and the smaller gears, V, are covered by rearward extensions of the plate T', for a purpose to be presently explained. The shaft X is further provided with three pulleys, e, between the plain faces of the gear-wheels W, the said pulleys being of much

less diameter than the gear-wheels. Pulleys f are journaled loosely on short shafts g, which are secured in the upturned ends of the rods T, as shown in Figs. 1 and 4. The pulleys f are somewhat larger than the pulleys e. Endless belts h pass around the pulleys e f and travel over and between the inner and the outer pairs of rollers O, the belts being provided with blocks to which are hinged the fingers i, which extend across the spaces between the several pairs of shields O', so that they will, when carried rearward by their belts, draw the ears rearward over the plate T' as far as the gears W, when the ears will pass to the plain wheels X', which are in a somewhat lower plane than the plate T', and the said wheels X' will cause the ears to pass over them into and through downward-inclined chutes K to the endless carrier L, carried by pulleys 6 and 7, journaled to the rear cross-bar of the frame B. The pulleys e, sprocket-wheel Y, and the intermediate gearing between said wheel and axle are so proportioned that the endless belts h will be moved rearward at the same rate of speed as the machine moves forward, for a purpose to be presently described.

As the fingers i pass between the gear-wheels W, they are folded toward each other, as shown in Figs. 1 and 3, and after passing said gear-wheels they hang down, as shown in Fig. 4; but when they reach the forward pulleys, f, they are forced apart by means of the converging downward-curved ends t' of the rods t. The said rods extend rearward, where they are bent back upon themselves and passed through the supporting cross-bars u, supported above the plate T' by uprights u', secured to the side bars of the frame B.

The shaft X has secured to it a bevel gear-wheel, 1, which meshes with a bevel-pinion, 2, mounted on a short shaft, 3, journaled in the bar B ^{2} and provided on its outer end with a pinion, 4, meshing with a pinion, 5, on the inner pulley-shaft of the carrier. The inner end of the carrier L delivers the ears upon an endless conveyer or elevator, M, passing around pulleys journaled at the opposite ends of the inclined frame M'. The frame M' is supported at its lower end by two rods, M ^{2} , one only being shown, (see Fig. 3,) pivotally connected at their ends to the carrier-frame and frame M', so that when the frame B and its parts are raised the elevator or conveyer frame will also be raised and the disengagement of the gearing prevented. The lower under edges of the frame M' are provided with a slotted box, M ^{3} , through which the bolt 10 from the frame A passes to firmly secure and support the upper part of said frame M' in its adjusted position. I would also state that in practice the several guide-posts A ^{3} are all curved forward on arcs concentric with the sprocket-wheel a^4 , so that the relative positions of the sprocket-wheels a^4 Y will not be changed when the frame B is adjusted.

The conveyer M is driven from the pulley

6 by means of a belt, 8, extending around the pulley 9 on its lower pulley-shaft, as shown in Fig. 3.

The upper and lower ends of the inclined 5 sliding frames R have shafts r journaled therein, and around pulleys on the outer ends of said shafts pass the endless belts R', which are provided with a suitable number of spikes or teeth. The upper shafts r also have inner 10 pulleys, r', around which and pulleys r² on the rear shaft, X, pass the endless belts R², for operating the toothed belts R'.

R³ is a spring-pressed belt-tightening pulley mounted in a suitable bracket on the frame 15 B, one being provided for each belt R², so that as the frames R move upward the slack of the belts R² will be taken up. The lower pulley-shafts r also carry the loose wheels R⁴, which run on the ground.

20 The machine, having been first properly adjusted, will operate as follows: The cornstalks will pass between the pairs of rollers, which are in practice two inches in diameter from rib to rib, and the rollers of each pair being 25 five-eighths of an inch apart. The space between the adjacent edges of each pair of shields O is in practice one and one-fourth inch, so as the rollers draw the stalk downward they will firmly grasp the stem and the husks adhering thereto, and as the butt of the ear rests on the edges of the shields the ear will not only be forced from the stem, but it will be husked at the same time. I would state here that I have demonstrated by a working ma-

35 chine the practicability of the above-described construction. The ears of husked corn will now rest in the trough or space between the shields, the distance between each pair of shields being in practice less than the diameter 40 of a small ear of corn—that is to say, about an inch and a quarter—as before stated. The fingers i will now push the ears rearward over the plate T' to the plain wheels X', over which they pass to the carrier L, as before described.

45 The fingers i will assist the entrance of the stalks between the rollers, as they steady the stalks and do not incline them rearward, but hold them in vertical positions. This is due to the fact that the belts move rearward at the 50 same rate of speed as the machine moves forward, and by thus holding the stalks in a vertical position the ears are properly presented to the husking-rollers, it being essential to the proper husking of the ears that

55 they be presented to the rollers in as nearly a vertical position as possible, so that the rollers may grasp the stem and adhering portions of the husks and squeeze out the ears. The fingers will be separated by the ends t' of 60 the rods t at the front of the machine, and, as the fingers pass under these rods while moving rearward, the rods will serve as guides and prevent the stalks or ears from throwing the fingers upward out of place, and the fingers i 65 will also be folded as they pass between the plain faces of the gears W at the rear of the

machine, as before stated. The supporting rods or bars T will also serve to protect, to some extent, the hanging fingers on the lower sides of the belt. As the machine moves forward, 70 the lower ends of the belts R², carried by the rearward, inclined frames R, will engage the "down" cornstalks at or near their roots and raise them, so that by the time the stalks have assumed vertical positions the forward movement of the machine will have brought the guides P S over the hills or roots of the stalks, and the fingers i will now assist their entrance between the rollers and also hold them in an upright position until the ears are husked and 75 severed.

Having thus described my invention, what I claim as new, and desire to secure by Letters Patent, is—

1. The combination, with the parallel rollers of equal diameter, spaced to grasp the stalks of the corn and the stems and husks of the ears, and having longitudinal ribs, and mechanism for rotating them in opposite directions toward each other, of the curved shields over 90 the rollers, spaced to prevent husked ears from falling between the rollers, and provided with longitudinal guide-ribs, and the endless belts having the laterally-projecting fingers extending across said guide-ribs over the 95 spaces between the shields, substantially as set forth.

2. The combination, with the rollers spaced to grasp the stalks of corn, the stems of the ears, and the adhering husks, and mechanism 100 for rotating the rollers toward each other in opposite directions, and the shields above the rollers spaced to allow the rollers to husk the ears and then receive the husked ears within the trough formed between and above them, of 105 the endless belt having fingers projecting across said trough, a driving mechanism, a shaft having a pulley around which the said belt passes, and gearing, substantially as described, connecting said shaft with the driving 110 mechanism, said pulley and gearing being relatively proportioned to move the belt rearward at the same rate of speed as the machine moves forward, substantially as set forth, whereby the stalk will be held vertical while 115 being drawn downward between the rollers while the ears are being simultaneously stripped and husked.

3. In a corn-husking machine, the combination, with the main frame open at its front end 120 and the husking mechanism carried thereby, of forwardly and downwardly inclined elevator-frames mounted at opposite sides of said open front end and movable freely in the direction of their lengths, pulleys journaled in 125 the ends of said frames, and the wheels R⁴, journaled at the lower ends of said frames, and endless toothed belts on said pulleys, and means for operating said belts to raise down stalks, whereby the said frames will rise and fall according to the inequalities in the ground, substantially as set forth.

4. The combination, with pairs of rollers and gearing for rotating the rollers of each pair in opposite directions toward each other, of endless belts traveling between the pairs of rollers and having fingers projecting laterally beyond their opposite sides and extending into or across the spaces above each pair of rollers, substantially as set forth.
5. The combination, with the rollers and their operating mechanism, of an endless belt having hinged outwardly-extending fingers extending across the space between and above the rollers, and rods or bars above the belt and converging at their forward downward-curved ends to separate and throw the fingers outwardly at the front upper side of the belt, substantially as set forth.
6. The combination, with the pairs of rollers and mechanism for rotating the rollers of each pair in opposite directions toward each other, of the endless belt having hinged fingers extending across the opening between and above the rollers, and the longitudinally-extending rods or bars extending from the rear end of the belt forward and curved downward and joined at their forward ends to form separators and guides for the fingers above the belt, substantially as set forth.
7. The combination, with the frame open at its front end, the pair of longitudinally-extending rollers journaled therein, and mechanism for rotating them in opposite directions toward each other, of the inclined slotted frames having a free sliding movement at the opposite sides of the forward ends of the frame, the bolts extending through the said slots into the said forward ends, spiked or toothed endless belts carried by said frames, and means for operating said belts, substantially as set forth.
8. The combination of the frame B, open at its front end, the shaft X, journaled near the rear end thereof and having the pairs of gear-wheels W, and pulleys e between each pair of gear-wheels and of less diameter than said wheels, the pairs of rollers O, having pinions V, meshing with wheels W, the longitudinally-extending rods or bars T, having pulleys f at their upturned forward ends, the endless belts h on said rollers and having fingers i, extending over the spaces between the pairs of rollers, the guides P for the outer rollers, the guides S, and the chutes K, leading rearward from between each pair of gear-wheels W to receive the ears from spaces above each pair of rollers, substantially as set forth.
9. The combination, with the frame A, having the axle a and drive-wheels a' a', and the
- guide posts or bars A³, of the vertically-adjustable frame B, sliding on the said posts A³ at its inner side, the vertically-adjustable guide C at the outer side of the frame B, and the adjustable wheel b, clamped thereto, the stripping and husking rollers O on the frame B, and the shaft X, for operating said rollers and driven indirectly from the axle a, substantially as set forth.
10. The combination, with the frame A, having the drive-wheels, of the vertically-adjustable frame B, open at its front end, the rollers O, having pinions V at their rear ends, the shaft X on frame B and having the gear-wheels W, meshing with the pinions V, the pulleys e between each pair of wheels W, and the plain wheels X' between the wheels W of each pair, the pulleys f, supported at the front ends of the rollers between the inner and outer pairs thereof, the endless belts h upon the pulleys e f and having the fingers i, folded by the wheels W in the rearward movement of the belts, the chutes K behind plain wheels X', and the plate T', covering the rear parts of the rollers O and the pinions V, substantially as set forth.
11. The combination, with the frame A, the wheels a', and axle a, of the vertically-adjustable frame B, the harvesting-rollers, the operating-shaft X at the rear end of the frame, intermediate gearing between the shaft X and axle a, the carrier L at the rear end of the frame B to receive the ears from the rollers, the elevator or conveyer frame M', rods M², connecting said frame to the carrier-frame, the slotted box M³ on the under side of the frame M', bolt 10, passing through said slot and the rear bar of frame A, and the gearing operating the carrier and elevator belts from the shaft X, whereby when frame B is adjusted the operating-gearing will not be thrown out of gear, substantially as set forth.
12. The combination, with the frame B, open at its front, the shaft X, the rollers O, belts h, having fingers i, and the operating mechanism, of the vertically-sliding inclined frames R, the pulley-shafts r, the endless spiked belts R', the belts R², passing from shaft X to upper pulley-shafts on frames R, and the tension-pulleys R³, for automatically taking up slack in belts R² when the frames R move upward, substantially as set forth.
